UNITED STATES PATENT OFFICE

157,219

TAPE DISPENSER

Louis Vavrik, Rossford, Ohio, assignor to The Witte-Toledo Company, Toledo, Ohio, a corporation of Ohio

Application November 27, 1948, Serial No. 149,850

Term of patent 14 years

(Cl. D74—1)

To all whom it may concern:

Be it known that I, Louis Vavrik, a citizen of the United States, residing at Rossford, in the county of Wood and State of Ohio, have invented a new, original, and ornamental Design for a Tape Dispenser, of which the following is a specification, reference being had to the accompanying drawing, forming part thereof.

Fig. 1 is a perspective view of a tape dispenser showing my new design. Fig. 2 is a top plan view thereof. Fig. 3 is a front end view thereof. Fig. 4 is a rear end view thereof.

I claim:

The ornamental design for a tape dispenser, as shown.

LOUIS VAVRIK.
